SAND DISTRIBUTOR

Joseph Rome, Barre, Vt.

Application December 7, 1946, Serial No. 714,740

14 Claims. (Cl. 291—27)

1

This invention pertains to road sanding apparatus for use with automotive vehicles and is designed to deposit sand in the angle between the road and the vehicle tread thereby to prevent skidding or to improve the wheel traction.

Apparatus of this type, as heretofore proposed, has often been of complicated and expensive character and in many instances requires serious structural changes in the vehicle in order that it may be applied. Furthermore, many such devices heretofore suggested, so far as is known to me, have not been dependable under the conditions of daily use. Unless the sand employed be carefully sifted and graded for size, it will not flow at a uniform rate, even when dry, by gravity action, and when moist or non-uniform in grain size or when contaminated with clay or other impurities it tends to bridge and clog the delivery passages. These difficulties are increased in cold weather by the freezing of moisture which may bind the granular particles together.

Among the objects of the present invention is to provide sanding apparatus of a simple type, capable of application without difficulty to existing automotive vehicles. A further object is to provide sanding apparatus which is dependable in operation and which will deliver ungraded and moist sand. A further object is to provide sanding apparatus having provision for removing sand mechanically from a sand reservoir at a predetermined rate so long as any sand remains to be delivered. A further object is to provide sanding apparatus comprising means operative mechanically to transfer sand from a reservoir to a delivery passage and which does not become clogged with sand even though the sand may be moist or dirty. A further object is to provide sanding apparatus operative to deliver sand onto the roadway in the angle between the road and the descending wheel tread, and so devised that the delivery chute is not readily injured mechanically nor clogged with frozen moisture from the road. A further object is to provide sanding apparatus capable of application, either to a passenger vehicle or truck, and having motor-driven means for removing the sand from the reservoir, the motor which drives the sand-removing means being controlled by a switch readily accessible to the driver. Other objects and advantages of the invention will be pointed out in the following more detailed description and by reference to the accompanying drawings wherein.

Fig. 1 is a fragmentary side elevation of a passenger automobile showing the sanding apparatus of the present invention (more or less dia-

2

grammatically) mounted upon the mudguard or fender of the right-hand rear wheel of a vehicle, the outer casing of the sanding apparatus being broken away and the sand reservoir being shown in vertical section;

Fig. 2 is a fragmentary horizontal section substantially on the line 2—2 of Fig. 1;

Fig. 3 is a fragmentary front elevation showing the tread of the wheel of the motor vehicle and 10 showing the delivery chute of the sanding apparatus arranged at the outside of the wheel so as to discharge sand directly beneath the wheel tread; and

Fig. 4 is a side elevation, to larger scale, of 15 the sand-removing device removed from the other parts.

Referring to the drawings, the numeral 1 designates the body of a passenger automobile having the right-hand rear wheel 2 provided with 20 the tread surface 3. The vehicle body is furnished with a mudguard or fender 4 which, in accordance with the present invention constitutes a support for and a part of the wall of the casing 5 of the sanding mechanism. This casing 5 may 25 be an integral portion of the mudguard 4 or attached to the outer surface of a standard mudguard. The left-hand rear wheel, while not shown, will obviously be provided with sand distributing means embodying the present invention, such as is here shown by way of example as applied to the right-hand rear wheel.

The casing 5 houses a sand reservoir 6, here shown as provided with the rear arcuate wall 7; the upwardly and forwardly inclined bottom 35 wall 8; and substantially vertical parallel and laterally spaced side walls 9 and 10, respectively, the wall 10, as here shown, being a part of the fender 4. The sand reservoir or receptacle is furnished with a cover 11 through which sand 40 may be introduced into the reservoir.

From the forward part of the reservoir a delivery tube 12, preferably of substantially rectangular horizontal section, extends downwardly and 45 preferably vertically to a point near the wheel tread. As here illustrated this tube comprises the rear wall 13 which is integrally joined to the bottom wall 8 of the reservoir at the junction point 14. This junction point defines the bottom of the entrance 16 to the delivery tube 12. The tube 12 has the forward wall 15 which extends upwardly, beyond said entrance, to the top of the reservoir, the cover 11 preferably being hinged to the upper edge of this wall 15.

Above the junction point 14 of the walls 8 50 and 13 there is arranged a horizontal shaft 17

which may be journaled in the side walls 8 and 10 of the reservoir, the axis of the shaft substantially defining the top of the entrance 16 to the delivery tube. This shaft 17 forms a pivotal support for an elongate rigid carrier 18 which is disposed between the walls 8 and 10 of the reservoir and which extends substantially to the arcuate wall 7 of the reservoir. This wall 7 is curved concentrically with the axis of the shaft 17 so that the free or rear end portion of the carrier 18 may swing downwardly from the position of Fig. 1 until it is substantially parallel to the bottom wall 8 of the reservoir, said end remaining at substantially the same distance from the inner surface of the wall 7.

A sprocket wheel 19 is fixed to the shaft 17 between the walls 7 and 10 of the reservoir, and a second sprocket wheel 20 is mounted to turn on a shaft carried by the free or rear end of the carrier 18. Preferably the carrier 18 is of adjustable length, the adjustment being accomplished by means of a screw 21 (Fig. 4) or equivalent device. An endless chain is trained about the sprocket wheels 19 and 20, this chain being formed of pivotally connected links 22. The shaft 17 is provided with a sprocket wheel 23 which is engaged by a sprocket chain driven by an electric motor 24 mounted on the vehicle body at any convenient point, here shown within the mudguard 4. This motor is connected by suitable conductors to a switch 25 (Fig. 1) located conveniently to the operator of the vehicle and is supplied with current from the electrical system of the vehicle. By closing the switch the motor 24 is energized, thus driving the shaft 17, the arrangement being such that when the shaft 17 is driven the lower run of the chain is caused to move toward the entrance 16 to the delivery passage in the tube 12.

Recurrent links of the chain mounted on the carrier 18 have outstanding brackets 26 to which are secured scraper blades 27. These blades are of stiff sheet material, for example stainless steel, each comprising an elongate body portion of a width such as to reach substantially from one of the side walls of the reservoir to the other. The body portion of each blade 27 is inclined with relation to the path of travel of the chain, the inclination being such that in the lower run of the chain the body portion of the blade inclines upwardly and forwardly. The forward edge of each scraper blade is preferably curved so as to contact the lower run of the chain, the blade thus acting like a ski to ride up and over the sand, while the rear edge portion 28 of each blade is curved in the opposite direction, so that in the lower run of the chain, the curved rear edges extend downwardly to constitute scraper elements for engagement with the body 8 of sand in the reservoir. The blades extend substantially from one side wall of the reservoir to the other and the blades at the lower run of the chain overlap and collectively form a continuous surface. Thus the sand within the reservoir can not directly contact the chain. The series of blades collectively constitute a sort of float resting on the surface of the sand so that the chain can not bury itself in the sand, the chain being held above the surface of the sand and with the blades intervening between it and the sand so that the chain is shielded from the sand and is not clogged by sand or small stones entering between its links. Such small amount of sand as may accidentally enter the space above the series of overlapping

blades, for example at the side of the conveyor, is discharged as the blades separate in passing about the sprocket wheel 19. If desired, anti-friction supports for the chain may be arranged intermediate the sprocket wheels 19 and 20.

Spaced below the lower end of the delivery tube 12 there is arranged an inclined chute 32, preferably substantially flat, although if desired it may be curved and may have upstanding flanges at its forward and rear edges. This chute is preferably supported yieldably so that if subjected to blows it may yield without bending or breaking and will return to its operative position automatically. With this object in view it is preferred to support this chute 32 by means of a plurality of stiff coiled springs 33 and 34, (Fig. 3) fixed at their upper ends to the casing 5, or other convenient part, and secured at their lower ends to the chute 32. Preferably these springs or other resilient supports are housed within a jacket 34 of flexible material, for instance waterproofed textile fabric, thereby to protect the springs and the chute from accumulations of mud, frozen snow or the like. As illustrated in Fig. 3, the chute is disposed laterally of the wheel and so inclined that sand which falls freely upon it from the discharge end of the delivery tube 12 bounces off into operative relation to the downwardly moving tread of the wheel. While this arrangement is desirable for use on passenger automobiles, it may be preferable, when mounting the device upon a truck body, to arrange the delivery chute 32 directly in front of the wheel treads so that on a multiple wheel vehicle, sand may be delivered beneath the treads of adjacent wheels. Obviously the reservoir, delivery tube and deflector may be located upon any desired and convenient part of the vehicle, but in any event so that sand, which is thrown off from the deflector, will be delivered in operative relation to the tread of the wheel so as to provide the improved traction effect.

While an endless chain is here illustrated as a desirable way of supporting and moving the scraper blades 27 it is contemplated that an endless flexible belt may be used and that scraper blades of other types may be employed. The chain and blade construction herein illustrated and specifically described is not readily clogged by the accumulation of sand. Any sand which accidentally enters the space between the blades and the chain is automatically discharged as the blades open away from each other in passing upwardly about the sprocket 18.

The arrangement is such, as herein disclosed, that the weight of the carrier 18, with its chain and blades, is for the most part supported by the body 8 of sand in the reservoir, the left-hand or rear end of the carrier 18 being wholly unsupported except by the sand, the overlapping blades collectively forming a shield which floats upon the sand and which substantially prevents the sand from contacting the links of the chain so that clogging of the chain is avoided. As the chain is driven, the scraper elements 28 move along the upper surface of the body of sand in the reservoir and positively drag the sand along to the entrance 16 to the delivery tube 12. The sand which enters this entrance falls freely down through the tube 12, the transverse horizontal dimensions of which are greater than those of the entrance 16, so that any sand which enters the upper end of the tube has ample room to fall without danger of clogging. As the freely

alling sand leaves the lower end of the delivery tube it drops onto the chute 32 and is thus deflected against or into the path of the wheel.

As the body of sand in the reservoir gradually diminishes, the carrier 18 swings downwardly about the shaft 17 as an axis so that the blades 21 continue to drag along the upper surface of the sand body and thus to deliver sand into the tube 12 until the entire supply of sand is exhausted. Throughout this operation the transfer of the sand from the reservoir into the delivery tube is wholly mechanical and not dependent upon gravity. The blades 21 are preferably somewhat flexible and resilient and thus are effective, even though the sand is not of uniform grain size and even though the sand may contain impurities, such for example as clay.

While the sand delivery means here disclosed is useful for the particular purpose described, that is to say to discharge sand from a reservoir to a point beneath the wheel of a motor vehicle, it is contemplated that the sand-discharging means, that is to say the pivoted carrier 18 with its blades, or its equivalent, may be found of utility in discharging sand from a reservoir or pile for other purposes and it is contemplated that such other uses of this sand discharging or transfer means fall within the scope of the present invention as defined in the appended claims.

I claim:

1. A road sander for sanding the road in advance of the wheel of a motor vehicle, said sander comprising a casing forming a lateral extension of the mudguard of the vehicle wheel, a sand reservoir within the casing, the reservoir, in front-to-rear vertical section, being substantially segmental in contour and having substantially parallel vertical side walls, an arcuate rear wall and a forwardly and upwardly inclined bottom wall, means including a rear wall defining a downwardly directed delivery passage, the rear wall of said passage being joined at its front end to the forward end of the inclined bottom wall of the reservoir, the junction of said walls defining the bottom of the entrance to the delivery passage, an elongate carrier within the reservoir, one end of the carrier being pivoted to turn about a horizontal axis located substantially at the top of the entrance to the delivery passage, the carrier being of such length that its free end is adjacent to the arcuate wall of the reservoir, said wall being concentric with the pivotal axis of the carrier, an endless chain supported by the carrier, sand-scraping blades carried by the chain, said blades being of a width to reach substantially from one side wall to the other of the reservoir, and motor means driving the chain so that its lower run moves toward the entrance to the delivery passage, the free end of the carrier with its chain being designed to rest upon and to be supported solely by the sand in the reservoir.

2. A road sander for sanding the road in advance of the wheel of a motor vehicle, said sander comprising a casing forming a lateral extension of the mudguard of the vehicle wheel, a sand reservoir within the casing, the reservoir, in front-to-rear vertical section, being substantially segmental in contour and having substantially parallel vertical side walls, an arcuate rear wall and a forwardly and upwardly inclined bottom wall, means defining a substantially vertical delivery passage having an entrance at its upper end, an elongate carrier within the reservoir,

one end of the carrier being pivoted to turn about a horizontal axis located substantially at the top of the entrance to the delivery passage, the carrier being of such length that its free end is adjacent to the arcuate wall of the reservoir, said wall being concentric with the pivotal axis of the carrier, and motor-driven means on the carrier for transferring sand from the reservoir to the entrance to the delivery passage.

3. In combination in sand delivery apparatus designed to remove sand from the upper surface of a body of sand and including a motor driven endless chain and spaced sprocket wheels turning about parallel, horizontal axes for guiding the chain so that its lower run overlies the sand body, a series of ski-like blades each having a substantially flat body portion elongate in the direction of chain motion, each blade having an upwardly curved forward edge designed to ride up over the sand, means attaching the body portions of the blades to the chain, the attaching means being so designed that the body of the blade is spaced from the chain, the rear edge of each blade being directed away from the chain and constituting a scraper for withdrawing sand from the sand body.

4. In combination in sand delivery apparatus designed to remove sand from the upper surface of a body of sand and including a motor driven endless chain and spaced sprocket wheels turning about parallel, horizontal axes for guiding the chain so that its lower run overlies the sand body, a series of ski-like blades carried by the chain, each blade having a scraper element at its rear end, those scraper elements which are at the lower run of the chain at any given time being operative to withdraw sand from the sand body, the ski-like blades constituting floats and being so constructed and arranged as by engagement with the sand to limit the depth to which their scraper elements may dip into the sand body.

5. A sand delivery apparatus comprising a sand reservoir, means defining a delivery passage, mean operative to transfer sand from the body of sand in the reservoir to the entrance to the delivery passage, said transfer means comprising an endless chain, a motor for driving the chain, and a series of substantially rigid blades carried by the chain, each blade comprising a substantially flat body portion which, in the lower run of the chain, is inclined upwardly in the direction of movement of the lower run of the chain, the advancing transverse margin of each blade being curved upwardly so that its edge contacts the lower run of the chain and the rearward margin of the blade being curved downwardly to form a scraper for engagement with the sand.

6. Sand delivery apparatus designed to remove sand from a body of sand at a predetermined rate which remains substantially uniform as the body of sand diminishes, said apparatus comprising an elongate carrier pivoted to swing about a horizontal axis at one side of the sand body, said carrier overlying the sand body, the free end of the carrier being supported solely by the sand body, an endless chain mounted on the carrier, the chain comprising a lower run which is below the carrier, means for driving the chain so that its lower run moves toward the pivotally supported end of the carrier, brackets carried by the chain at spaced intervals, a stiff blade so fixed at a point intermediate its transverse edges to each bracket that the body of the blade is spaced from

the chain, the forward margin of each blade being bent so that its free edge contacts the chain at a point spaced from the bracket thereby to brace the blade, and the rear margin of each blade being bent away from the chain to form a scraper element, the rear portion of each blade overlapping and contacting the forward portion of the next adjacent blade, thereby to shield the chain from direct contact with the sand.

7. Sand delivery apparatus of the kind which is designed to remove sand from a body of sand at a predetermined rate which remains substantially uniform as the body of sand diminishes, and including an elongate carrier pivoted to swing about a horizontal axis and which overlies the sand body with the free end of the carrier supported solely by the sand body and having an endless chain comprising pivotally connected links mounted on the carrier, said chain comprising a lower run which is below the carrier, characterized in that recurrent links of the chain have outwardly directed brackets and a blade so secured to each bracket that the body of the blade is spaced from the chain, the blades overlapping at the lower run of the chain to form a substantially continuous surface, each blade having a substantially flat body portion which in the lower run of the chain is inclined upwardly in the direction of movement of the lower run of the chain, the advancing edge of the blade being curved upwardly so as substantially to contact the lower run of the chain, and the rearward edge of the blade being curved downwardly to form a scraper for engagement with the sand.

8. A road sander for applying sand to a wheel of an automotive vehicle, said sander being of the kind wherein sand carried by the vehicle is transferred to the entrance to a delivery passage by power-driven means constructed and arranged to be mounted on the vehicle, the transfer means including an elongate carrier pivoted adjacent one end to turn about a horizontal axis, and wherein an endless chain is supported by the carrier and carries a series of scraper elements, characterized in having a series of independent ski-like parts, having turned-up forward ends, secured to recurrent links respectively of the chain and which ride upon the sand and collectively constitute a shield to prevent direct contact of the chain with the body of sand in the reservoir, said parts having turned-down rear ends which constitute the scraper elements.

9. Sand transfer means designed to remove sand from a reservoir, said transfer means comprising an endless power-driven link chain and spaced sprocket wheels partially embraced by the chain and constructed and arranged to guide the chain so that a substantially straight run of the chain overlies the body of the sand in the reservoir, and a series of independent blades each secured in spaced relation to one of the chain links, said blades being of such dimensions lengthwise of the chain that at said straight run of the chain the blades overlap to form a substantially continuous surface for contact with the sand, each of said blades having its rear edge deflected downwardly so that it constitutes a scraper operative to drag the sand along in the direction of movement of said straight run of the conveyor.

10. Sand transfer means designed to remove sand from a reservoir of substantially uniform width, said transfer means comprising a series of ski-like blades and an endless power-driven conveyor supporting said blades and arranged to

move them in a path comprising a substantially straight run which overlies the sand in the reservoir, the blades being so dimensioned as to extend transversely substantially from one side to the other of the reservoir and at said straight run to overlap each other thereby to form a substantially continuous supporting surface to rest upon the sand, each blade comprising a downwardly projecting sand scraping element and an upwardly directed forward end.

11. Sand transfer means designed to remove sand from a reservoir, said transfer means comprising an endless power-driven chain having a substantially straight run which overlies the sand in the reservoir, a series of independent, substantially rigid parts carried by the chain, said parts comprising blade-like elements which overlap at the straight run of the chain thereby collectively forming a support for the chain and a shield to prevent direct contact of the chain with the sand and scraping elements which project below said shield.

12. Apparatus for delivering sand to improve the tire traction of a vehicle wheel, said apparatus including in combination, a sand reservoir comprising spaced side walls and a bottom wall, the bottom wall sloping upwardly toward the entrance to a delivery passage, an elongate carrier within the reservoir, one end of the carrier being pivoted to turn about a horizontal axis located adjacent to the upper end of the bottom wall and approximately at the maximum level of the sand in the reservoir, means defining a delivery passage whose entrance is adjacent to the pivoted end of the carrier, motor-driven means on the carrier for transferring sand from the reservoir to the entrance to the delivery passage, and an inclined deflector located below the discharge end of the delivery passage and which is operative to deflect sand, falling freely thereon, into operative relation to the tire tread.

13. Apparatus for delivering sand to improve the tire traction of a vehicle wheel, said apparatus including in combination, a sand reservoir mounted on the vehicle, the reservoir comprising spaced, vertical side walls, an arcuate rear wall, and an inclined bottom wall which slopes upwardly and forwardly toward a delivery passage, means, including a substantially vertical wall, defining a downwardly directed delivery passage, said vertical wall being joined to the upper end of the inclined bottom wall of the reservoir, the junction of said walls defining the bottom of the entrance to the delivery passage, an elongate carrier within the reservoir, one end of the carrier being pivoted to turnabout a horizontal axis located close to the upper end of the bottom wall of the reservoir and substantially at the top of the entrance to the delivery passage, motor driven means on the carrier for transferring sand from the reservoir to the entrance to the delivery passage, and deflector means, below the discharge end of the delivery passage, arranged to deliver sand falling freely thereon into operative relation to the tire tread.

14. Apparatus for delivering sand to improve the tire traction of a vehicle wheel, said apparatus including in combination, a sand reservoir mounted on the vehicle, the reservoir comprising spaced, vertical side walls and an inclined bottom wall, the bottom wall sloping upwardly toward a delivery passage, means defining a substantially vertical delivery passage having its entrance adjacent to the upper end of the inclined bottom wall of the sand reservoir, an elongate

carrier within the sand reservoir, one end of the carrier being pivoted to turn about a horizontal axis located substantially at the top of the entrance to the delivery passage, an endless chain supported by the carrier, sand scraping blades carried by the chain said blades being of a width to reach substantially from one side wall to the other of the reservoir, and motor means driving the chain so that its lower run moves toward the entrance to the delivery passage, the free end of the carrier with its chain being designed to rest upon and to be supported solely by the sand in the reservoir.
